(57) **CLAIM**

We claim the ornamental design for a front pad of an internal padding assembly of a football helmet, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a front pad of an internal padding assembly of a football helmet, showing an exterior surface of pad.

FIG. 2 is a rear view of the front pad of an internal padding assembly of a football helmet of FIG. 1, showing an interior surface of pad.

FIG. 3 is a top view of the front pad of an internal padding assembly of a football helmet of FIG. 1.

FIG. 4 is a bottom view of the front pad of an internal padding assembly of a football helmet of FIG. 1.

FIG. 5 is a left side view of the front pad of an internal padding assembly of a football helmet of FIG. 1; and, FIG. 6 is a right side view of the front pad of an internal padding assembly of a football helmet of FIG. 1.

The dot-dash-dot (“- — -”) broken line in the Figures represents an unclaimed boundary of the front pad of an internal padding assembly of a football helmet. A first portion contained outside of the dot-dash-dot broken lines, illustrated in lighter tones, shows the first portion of the front pad of an internal padding assembly of a football helmet that forms no part of the claimed design. A second portion contained inside of the dot-dash-dot broken lines shows the
